METHOD OF FILLING TANKS WITH COMPRESSED GAS

Filed July 14, 1928

INVENTOR:
Chester Mott,
BY *Fred W. Davis*

ATTORNEY.

UNITED STATES PATENT OFFICE

CHESTER MOTT, OF DENVER, COLORADO, ASSIGNOR, BY MESNE ASSIGNMENTS, TO UNION CARBIDE AND CARBON RESEARCH LABORATORIES, INC., A CORPORATION OF NEW YORK

METHOD OF FILLING TANKS WITH COMPRESSED GAS

Application filed July 14, 1928. Serial No. 292,817.

This invention relates to a method of and apparatus for filling tanks with a compressed gas from other containers in which the gaseous substance is held as a liquid.

One of the objects of the invention is to render possible the wider economic distribution of gaseous oxygen. Under present conditions, high freight rates on the compressed gas often make it impossible economically to distribute the gas over a wide area. With the aid of the present invention, liquid oxygen in containers can be shipped to distribution points for gas cylinders and the latter can be shipped from there.

Another object of the invention is to make it possible to bring a filled gas cylinder to a sufficiently high pressure so that a relatively large quantity of gas can be forced into the cylinder.

The accompanying drawing shows an assemblage of apparatus whereby my objects may be attained. The view is a side elevation, partly in section.

5 A gas storage means in the form of a cylinder 10, shown on the left, is filled with a compressed gas, which may be oxygen. None of the gas in this cylinder is in liquid form. 11 is the usual escape valve on cylinders of this type and 12 is a reducing valve of the ordinary kind. The metal pipe 13 leads into a container of liquid oxygen 14 and terminates at the nozzle of a jet pump in the form of an injector 15 below the level 15 of the liquid oxygen and preferably as near the bottom of the container as possible. This injector, shown diagrammatically, is not different in principle or construction from the usual injector for steam boilers, except that it is of small enough size to go 40 through the neck of the liquid oxygen container.

A second pipe 17 leads from the injector to a receiver in the form of a cylinder 18 45 which is to be filled. This pipe is of some-

what larger diameter than that of pipe 13, since it must carry a large volume of gas. No special valves are necessary on either the pipe 17 or the cylinder 18, but the ordinary valve 19 of that cylinder must be of a capacity equal to or greater than pipe 17. In cold climates, means for heating any or all of the containers may be provided.

In operation, the above apparatus functions as follows: Cylinder 10 contains gas at 55 a high pressure while cylinder 18 may contain gas at somewhat lower pressure or be entirely empty. Valves 11, 12, and 19 are opened and the pressure at the reducing valve 12 regulated in accordance with the speed at 60 which it is desired to fill cylinder 18. The stream of gas flowing through pipe 13 has, at the injector, a combined vaporizing and entraining action. That is to say, globules of liquid oxygen are sucked into the injector 65 and are partially vaporized in it, the pipe 17 and cylinder 18. The result is that the cylinder 18 is eventually filled with a bottom layer of liquid oxygen with a layer of gas above 70 it, the gas being at a relatively low pressure. Since it is the object of the invention to fill cylinders with gas, some means to vaporize the liquid oxygen is generally necessary. The atmospheric temperature and the fullness of the cylinder are the governing factors. If 75 the atmospheric temperature is high, the cylinder may be allowed to attain equilibrium by itself. In cold climates it is necessary to heat the filled cylinders slightly, preferably by putting them in a warm room. In no case should the heating temperature be over 100° F. on account of the danger of explosion. The result of the heating is that all of the liquid oxygen is vaporized and the gas pressure is materially increased.

Obviously substances other than oxygen may be used in both the containers 10 and 14, and it is not necessary that the container 14 contain liquefied gases of the same composition as those gases in the container 10, for 90

blending or mixing effects are also a part of this invention.

I claim as my invention:

1. A method of filling a receiver with a gas which includes the steps of: entraining in a stream of said gas particles of this gas in liquefied form; introducing the mixture into said receiver; and vaporizing the liquid in said receiver to raise the pressure in said receiver.

15 2. A method of filling a receiver with oxygen which includes the steps of: introducing into said receiver a mixture of liquid and gaseous oxygen; and heating said receiver to vaporize the liquid oxygen delivered thereto in said mixture.

15 In testimony whereof, I have hereunto set my hand at Denver, Colorado, this 5 day of July, 1928.
